EXPANSIBLE WRIST WATCH BRACELET

John F. Sand, Convent Station, N. J., assignor to The Gemex Corporation, Union, N. J., a corporation of New Jersey

Application April 4, 1956, Serial No. 40,895

Term of patent 14 years

(Cl. D45—4)

FIG. 1.

FIG. 2.

FIG. 3.

FIG. 4.

FIG. 5.

FIG. 6.

FIG. 7.

Fig. 1 is a top plan view of an expansible wrist watch bracelet embodying my new design;

Fig. 2 is an edge view thereof;

Fig. 3 is a bottom plan view thereof;

Fig. 4 is a top plan view of the bracelet in an expanded condition;

Fig. 5 is an edge view of Fig. 4;

Fig. 6 is a bottom plan view of Fig. 4; and

Fig. 7 is a perspective view of part of the bracelet.

I claim:

The ornamental design for an expansible wrist watch bracelet, substantially as shown.
